(57) **CLAIM**

The ornamental design for a tent, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a tent with openings for ingress and egress spaced equidistantly apart.

FIG. 2 is a right side elevational view of the tent shown in FIG. 1.

FIG. 3 is a left side elevational view of the tent shown in FIG. 1; and,

FIG. 4 is a rear perspective view of the tent shown in FIG. 1.

The broken line shown throughout the drawings forms no part of the claimed design.
